UNITED STATES PATENT OFFICE.

SAMUEL SAMPSON, OF NEW YORK, N. Y.

DESIGN FOR A BELT BUCKLE.

Application filed June 21, 1928. Serial No. 27,216. Term of patent 3½ years.

To all whom it may concern:

Be it known that I, SAMUEL SAMPSON, a citizen of the United States, residing at New York city, in the county and State of New York, have invented a new, original, and ornamental Design for a Belt Buckle, of which the following is a specification, reference being had to the accompanying drawing, forming part thereof, and in which—

Fig. 1 is an end view of a belt buckle showing my new design; and Fig. 2 is a face view of the same.

I claim:

The ornamental design for a belt buckle as shown.

SAMUEL SAMPSON.
